CLAIM

The ornamental design for a tire, as shown and described.

DESCRIPTION

FIG. 1 is a front perspective view of the tire showing my new invention;

FIG. 2 is a front elevation view thereof;

FIG. 3 is an enlarged partial front elevation view thereof;

FIG. 4 is a left side elevation view thereof; and,

FIG. 5 is a right side elevation view thereof.

The dash-dot broken line bracket shows the portion of FIG. 2 from which the enlarged view of FIG. 3 is taken and forms no part of the claimed design.
